UNITED STATES PATENT OFFICE.

ELMER BEAVERS, OF WALTHAM, AND WILLIAM A. WEBBER, OF WATERTOWN,
MASSACHUSETTS, ASSIGNORS TO SANI-TITE CAP COMPANY, OF BOSTON,
MASSACHUSETTS, A CORPORATION OF MASSACHUSETTS.

LINING FOR JAR-CAPS AND METHOD OF SEALING JARS.

1,382,051.

Specification of Letters Patent. Patented June 21, 1921.

Application filed June 30, 1919. Serial No. 307,835.

To all whom it may concern:

Be it known that we, ELMER BEAVERS and WILLIAM A. WEBBER, citizens of the United States of America, the former residing at 5 Waltham, the latter at Watertown, both in the county of Middlesex and State of Massachusetts, have invented new and useful Improvements in Linings for Jar-Caps and Methods of Sealing Jars, of which the following is a specification.

The object of the invention is to provide an inexpensive and efficient lining for the caps of fruit jars and similar receptacles which shall be replaceable or renewable after 15 each use of the jar or container, which shall effectually prevent contact between the contents of the jar and the metal of the cap, which shall effectually prevent the escape of liquid or other contents of the jar, and which 20 shall constitute a hermetic sealing agent for the joint between the cap and the jar so as to prevent the entrance of air.

In the present practice it is common to use jar caps or covers having permanent linings of non-corrosive material such as porcelain or the like depending upon a rubber ring or gasket at the seal between the cover rim bracket usually threaded upon the jar neck in the bracket and the shoulder of the 30 jar to exclude air after the jar has been closed, but not only is there an element of uncertainty with regard to the efficiency of the air seal provided by the rubber gasket, but owing to the fact that the porcelain 35 or other lining of the cap does not seat upon and form a moisture proof joint with the neck of the jar, and there is a tendency for the said lining to become more or less loose from the metal of the cap, the liquid contents of the jar finding their way to the metal and owing to the acid content thereof in the event of fruit or vegetables constituting the contents of the jar, there is at once induced a reaction resulting in a more or 45 less injurious compound or poison which affects the contents of the jar and the least injurious effect of this contact and contamination is to cause the deterioration or decomposition of the preserved fruit or vegetables.

It is the object of this invention to provide a lining for preventing contact under any circumstances of the contents liquid or otherwise of the jar with the metal or other ma-

terial constituting the cover and at the same time to provide a seal which supplements or may be substituted for that afforded by the rubber gasket, so as to positively exclude air from the interior of the jar after it has been closed, so as to prevent the deterioration of the contents by reason of oxidation and with this object in view the invention consists in a construction and combination of parts hereinafter specifically described, it being understood that changes in form and proportion, as well as details of materials, may be resorted to within the scope of the claims without departing from the principles involved.

In the drawing:

Figure 1 is a sectional view of a jar and cover having cover lining and sealing means embodying the invention applied in the operative position thereto.

Fig. 2 is a similar view showing the cover and the related parts or elements of the sealing and lining means separated from the jar in the relation which they occupy when in use.

The jar 10 and screw cap or cover 11 as illustrated are of the conventional forms now in common use in preserving fruits and vegetables by either the steam, sterilizing or cold packed methods, the shoulder of the jar being provided with the usual rubber seating gasket 12 for the contact of the lower edge of the flange or ring 13 of the cover as in the ordinary practice, although the use of such gasket is unnecessary under ordinary circumstances when the jars are provided with the cover lining and sealing means constituting the subject matter of this invention.

Disposed upon the mouth of the jar and adapted to be seated thereon immediately after the filling of the receptacle is a waxed or paraffined paper disk 14 having a slightly downturned peripheral flange or lip 15, and seated upon this disk is a second disk of wax or paraffin or of a soft or spongy vehicle such as blotting paper or the like impregnated or saturated with wax or paraffin under such conditions as to readily liberate the latter upon the application of a moderate degree of heat so that if the contents of the jar are packed in a hot state the disks being arranged as described having the cap and cover screwed into place, the heat of

the contents of the jar will soften the wax or paraffin in the upper or distributing disk and will cause the same to flow down over the lip of the inner or protecting disk and into the space between the flange of the cover and the neck of the jar or between the threads by which said parts are connected so as to constitute a hermetic seal. The overhanging lip of the protecting disk serves to prevent the wax or paraffin from running into the jar and directs it to the outside of the neck where it is disposed to constitute an effective seal. The heat also serves to soften the wax or paraffin with which the base or body of the protecting disk is formed, so that a jointure of the distributing and protecting disks is effected and the portion of the paraffin which flows outward over the peripheral lip of the protecting disk and into contact with the surface of the jar neck below the same, practically forms in connection with the amalgamated disks a complete sealing cap which to all intents and purposes is part of the jar neck and retains such condition and function so long as the temperature to which the jar is exposed is below the melting point of the paraffin.

Obviously in the removal of the cap or cover from the jar the seal is broken and the utility of the sealing means is destroyed, but it is the purpose to use the indicated sealing means only once, so that a new and sterile set of sealing elements may be employed in each subsequent use of the jar.

If the contents of the jar are prepared under the cold packed process or method it is necessary simply to dash hot water upon the cap after sealing the same on the jar to cause the distributing disk to soften sufficiently to form the seal as above described.

From the above description it will now be clear that the disk 16 impregnated with sufficient paraffin to flow into and close the joint between the skirt of the cap 11 and the neck of the jar as well as to seal the joint between said disk 16 and the chine of the jar mouth, is the essential and important feature of our invention. The disk 14 is not an essential element and may, if desired, be, and sometimes is, dispensed with. It has been common heretofore to insert a paraffined disk within the cap of a fruit jar or

like container, but such disks have only, heretofore, been provided with enough paraffin to render them impervious to the liquid contents of the jar or other container. In other words it has heretofore only been the practice to render the paper disk liquid proof by paraffining the same or coating it with shellac, varnish or the like. So far as we know we are the first to provide a disk 16 of paper or other suitable fibrous material which is impregnated or saturated with such a quantity of paraffin that when the paraffin is melted by the heat from the contents of the jar, or from any other source, not only is the joint between the disk 16 and the chine of the neck of the jar perfectly closed and sealed but the paraffin from the disk also flows down into the joint between the threaded skirt of the jar cap and the neck of the jar.

The invention having been described, what is claimed as new and useful is:

1. As a new article of manufacture a disk of sheet material adapted to be used within the cap or top of a fruit jar or the like, said disk being coated with a quantity of paraffin or the like sufficient to flow into and close the joint between the skirt of the jar cap and the neck of the jar when heat is applied thereto.

2. As a new article of manufacture a disk of fibrous material adapted to be used within the cap or top of a fruit jar or the like, said disk being impregnated with a quantity of paraffin or the like sufficient to flow into and close the joint between the skirt of the jar cap and the neck of the jar when heat is applied thereto.

3. The method of sealing fruit jars and the like which consists in first filling the jar, then applying the cap of the jar to the latter with a paraffin coated disk of sheet material within said cap and thereafter utilizing heat to melt the paraffin carried by the disk and causing the paraffin to flow downwardly around the neck of the jar or the like into the joint between said neck and the skirt of the cap.

In testimony whereof we affix our signatures.

ELMER BEAVERS.
WILLIAM A. WEBBER.
